UNITED STATES PATENT OFFICE.

OTTO KURZ, OF STURGIS, MICHIGAN, ASSIGNOR, BY MESNE ASSIGNMENTS, TO STURGIS STEEL GO-CART COMPANY, OF STURGIS, MICHIGAN.

GO-CART.

No. 882,895.

Specification of Letters Patent.

Patented March 24, 1908.

Application filed February 28, 1907. Serial No. 359,788.

To all whom it may concern:

Be it known that I, OTTO KURZ, a subject of the Emperor of Germany, residing at the village of Sturgis, county of St. Joseph, State 5 of Michigan, have invented certain new and useful Improvements in Go-Carts, of which the following is a specification.

This invention relates to improvements in children's carriages.

10 It relates particularly to improvements in folding carriages, such as are commonly designated as go-carts, although certain features are adapted for and desirable for use in other relations.

15 The objects of this invention are, first, to provide in a child's carriage of the class described an improved spring. Second, to provide an improved adjustable foot-rest with means for supporting and locking it in its 20 adjusted positions. Third, to provide in a structure of the class described an improved wheel lock. Fourth, to provide in a structure of the class described an improved locking means for holding the carriage in its collapsed or folded position. Fifth, to provide in a carriage an improved means for retaining the 25 wheels upon the axles.

Further objects, and objects relating to structural details, will definitely appear 30 from the detailed description to follow.

I accomplish the objects of my invention by the devices and means described in the following specification.

The invention is clearly defined and pointed out in the claims.

A structure embodying the features of my invention is clearly illustrated in the accompanying drawing, forming part of this specification, in which,

40 Figure 1 is a side elevation of my improved folding carriage, one of the forward wheels being removed and the adjustment of the foot-rest being indicated by dotted lines.

Fig. 2 is an enlarged detail side elevation 45 showing the foot-rest in its unlocked position, so that it can be adjusted either up or down.

Fig. 3 is an enlarged longitudinal section thereof taken on a line corresponding to line 3—3 of Fig. 4. Fig. 4 is a cross section thereof taken on a line corresponding to line 50 4—4 of Fig. 3. Fig. 5 is a detail side elevation of my improved carriage shown folded

or collapsed, the wheels being removed from one side to better show the arrangement of the parts. Fig. 6 is a detail side elevation, showing details of the foot-rest and means for holding the same. Fig. 7 is a detail front elevation of the structure when folded or collapsed. Fig. 8 is a detail section taken on a line corresponding to line 8—8 of Fig. 6. Fig. 9 is an enlarged section taken on a line corresponding to line 9—9 of Fig. 5, showing the locking means for retaining the 65 parts in their collapsed position. Fig. 10 is an enlarged section taken on a line corresponding to line 10—10 of Fig. 1, showing the means for retaining the wheel locking lever in its locking position. Fig. 11 is a detail 70 section taken on a line corresponding to line 11—11 of Fig. 1, showing details of the axle. Fig. 12 is an enlarged detail, the retaining ring for the wheels being shown in section. Fig. 13 is a sectional view through the axle, 75 the retaining ring being shown in full lines.

In the drawing, the sectional views are taken looking in the direction of the little arrows at the ends of the section lines, and similar reference characters refer to similar 80 parts throughout the several views.

Referring to the drawing, the side pieces 1 of the frame are relatively fixed or rigid and are provided with a handle at their upper ends. These side pieces are preferably curved 85 downwardly and forwardly at their lower ends. On the lower ends of the side pieces 1 is the axle for the forward wheels. The side pieces 2 of the frame are pivoted to the side pieces 1, and are adapted to swing thereon in 90 collapsing the carriage. The side pieces 2 are made up of sections 5 and 6 connected by a coupling 7. The coupling 7 is provided with a cylindrical portion at the top, below which are side parallel portions adapted to 95 receive the ends of the sections 5 and 6 which are secured thereon by rivets 8.

The coiled spring 9 is arranged in the casing above the piece sections and is adapted to engage the shoulders 10 formed thereon. 100 The casing 7 is shaped to receive the spring, so that the spring is retained by means of the shoulders 10. The casing is preferably made up of a piece of sheet metal folded at the top with its upper part bent into a cylindrical 105 form to receive the coiled spring and its sides brought parallel at the bottom to receive the ends of the side bar sections. The lower

edges of the coupling are preferably shaped and turned inwardly at 11 to form stops for limiting the movement of the sections therein. By this arrangement, a spring support is provided for the rear axle. It has been quite a common practice to support the rear axle by blade springs. It is found, however, in practice to be very difficult and expensive to produce and arrange these springs so that 10 the springs on both sides shall be exactly alike, and, if they are not alike, the wheels do not track.

The upper end of the side piece 2 is engaged in a longitudinal slot in the side rails 4, which is pivoted at their rear ends to the handle bars. The seat is carried by the arms 12, the upper ends of which are pivoted to the vertically-arranged links 3, the pivots for the arms 12 to the links being preferably 20 located opposite the forward edge of the seat-board. The links 3 are pivoted to the forward end of the side bars 20 and the side bars 20 are pivoted at their rear ends to the fixed side pieces 1 of the frame.

25 In collapsing the structure, the forward ends of the bars 20 are lifted upwardly, as clearly appears in Fig. 5. This swings the seat to a vertical position and the adjustable side pieces 2 are swung on their pivots to bring the rear wheels forward.

The side rails 4 are provided with upwardly projecting portions 21 at their rear ends having outwardly projecting lugs 22 thereon adapted to engage suitable holes 23 formed 35 therefor in the inside of the side pieces 1; see Figs. 1, 5 and 9. The projections 21 close inside of the handle.

The lugs or projections 22 snapping into the holes provided therefor effectively retains the parts, and, at the same time, they 40 are readily disengaged by merely swinging the upper ends of the side bars 20 forward.

The arms by which the foot-rest is carried are adapted to be swung into the position 45 shown by full lines in Fig. 1, or to the upper position shown by dotted lines therein. The foot-rest is locked in either of its adjusted positions and supported in its upper or elevated position by means of the bail-like lever 50 15, the arms 13 of which are pivoted to the supporting arms of the foot-rest.

The links 14 are pivotally connected to the arms 13 of the lever and to the lower ends of the links 3. The pivots for the links 14 are 55 so arranged that the pivots for the links to the lever 15 are swung past the center, both when the lever is swung down against the arms 12, as shown in Fig. 1, or when swung up against the same, as shown by dotted 60 lines in Fig. 1. To easily enable the securing of this result, the arms 13 of the levers are bent. By this means, the foot-rest is very rigidly supported and locked in either position. When it is desired to adjust the same, 65 the lever 15 is swung upwardly or down-

wardly, as the case may be, according to the position in which the foot-rest then is, to break the joint. The foot-rest may then be swung or adjusted freely, the same being locked in its adjusted position by swinging 70 the lever into place against the supporting arms.

To automatically fold the foot-rest, when the structure is collapsed, I provide the same with rearwardly projecting fingers 17 and 18 75 adapted to engage the trip 19 provided therefor on the side rails 4 of the seat, thereby swinging the foot - rest on its pivots, as clearly appears in Fig. 6. This, however, only takes place when the foot-rest is locked 80 in its lower position, as indicated in Fig. 1.

The wheels are retained upon the axles 25 by rings 27, which are clamped in suitable annular grooves formed therefor in the axles; see Figs. 11, 12 and 13. This effect- 85 ively secures the wheels upon the axles, obviating the necessity of drilling the axles to receive cotter pins, or threading the same to receive nuts, as has been the common practice.

It is obvious that the rings 27 may be 90 quickly applied and also the forming of said groove is a simple operation, thereby greatly reducing the expense of manufacture and also providing a superior structure.

A further advantage of securing the wheels in this manner is that the rings are free to revolve with the wheels in case there should be sufficient friction of the wheels thereon. I also provide a locking lever 28 for one of 100 the wheels. This lever is formed of spring metal and is pivoted at 29 on one of the side pieces 2 of the frame, and its lower end formed into a shoe adapted to engage the tire of one of the rear wheels. The lever is 105 formed of spring material, and its upper end is kinked outwardly at 31 to form a finger piece. The brake is provided with an inwardly projecting lug 32 adapted to engage in the suitable hole 33 provided therefor in 110 the side piece. By this simple method, I secure a simple and effective wheel lock or brake, which can be readily applied or released.

I have illustrated and described my improved collapsing carriage in detail in the form preferred by me on account of its structural simplicity and convenience. I am, however, aware that it is capable of considerable variation in structural details 120 without departing from my invention.

Having thus described my invention, what I claim as new and desire to secure by Letters Patent is:

1. The combination of downwardly, forwardly projecting fixed side pieces, having a handle at their upper ends; adjustable side pieces arranged across and pivoted to said fixed side pieces; axles carried by said side pieces; side rails slotted to receive the upper 130

ends of said adjustable side pieces, pivotally mounted on said fixed side pieces; vertically-arranged links pivoted at the forward end of said side rails; side bars pivoted to the upper 5 end of said vertically-arranged links and to said fixed side pieces, a seat carried by said side rails; a foot-rest; supporting arms therefor pivoted on said vertically-arranged links; means for locking said foot-rest in its adjusted 10 positions, comprising a bail-shaped lever pivoted to the said foot-rest supporting arms, links pivoted to said lever and to said vertically-arranged links, the said links having their pivots so arranged relative to the 15 pivots of said bail-like lever as to lock the foot-rest in either adjusted position.

2. The combination of a foot-rest; pivoted supporting arms therefor; means for locking said foot-rest in its adjusted positions, comprising a bail-shaped lever pivoted 20 to the said foot-rest supporting arms, links pivoted to said lever, the said links having their pivots so arranged relative to the pivots of said bail-shaped lever as to lock the foot 25 rest in either adjusted position.

3. The combination of the fixed side pieces; adjustable side pieces arranged across and pivoted to said fixed side pieces; axles carried by said fixed side pieces; side rails to which said adjustable side pieces are slidably connected, pivotally mounted on said fixed side pieces; vertically arranged links pivoted at the forward end of said side rails, connected at their upper ends to said fixed 35 side pieces; a seat carried by said side rails; a foot rest; pivoted supporting arms therefor; means for locking said foot rest in its adjusted position comprising a lever pivoted to said foot rest; and a link pivoted to said 40 lever and to said vertically arranged link, said link having its pivot so arranged relative to the pivot of said lever as to lock the foot rest in its adjusted position.

4. In a carriage, the combination with an 45 axle, of a support for said axle made up of sections, the meeting ends of the said sections being cut away on their upper edges to form shoulders; a coupling for said sections, having a cylindrical portion at the top and 50 parallel side portions adapted to receive the ends of said sections, the edges of the said side portions being V-shaped and provided with inturned flanges forming stops for limiting the movement of the said sections 55 therein; rivets for pivotally securing said sections in said coupling; and a coiled spring arranged in the cylindrical portion of said coupling between the shoulders on said sections, for the purpose specified.

5. In a carriage, the combination with an 60 axle, of a support for said axle made up of sections, the meeting ends of the said sections being cut away on their upper edges to form shoulders; a coupling for said sections 65 having a cylindrical portion at the top and

parallel side portions adapted to receive the ends of said sections; stops for limiting the movement of said sections in said coupling; rivets for pivotally securing said sections in said coupling; and a coiled spring arranged in the cylindrical portion of said coupling between the shoulders on said sections, for the purpose specified. 70

6. In a carriage, the combination with an axle, of a support for said axle made up of 75 sections, the meeting ends of the said sections being cut away to form shoulders; a coupling for said sections, having a cylindrical portion and parallel side portions adapted to receive the ends of said sections; rivets for pivotally securing said sections in said coupling; and a coiled spring arranged in the cylindrical portion of said coupling between the shoulders on said sections, for the purpose specified. 80

7. In a carriage, the combination with an axle, of a support for said axle made up of sections; a coupling for said sections, having a cylindrical portion and parallel side portions adapted to receive the ends of said sections, the edges of the said side portions being V-shaped and provided with inturned flanges forming stops for limiting the movement of the said sections therein; rivets for pivotally securing said sections in said coupling; and a coiled spring arranged in the cylindrical portion of said coupling to engage 85 said sections, for the purpose specified. 90

8. In a carriage, the combination with an axle, of a support for said axle made up of 100 sections; a coupling for said sections, having a cylindrical portion and parallel side portions adapted to receive the ends of said sections; stops for limiting the movement of said sections in said coupling; rivets for pivotally securing said sections in said coupling; and a coiled spring arranged in the cylindrical portion of said coupling to engage 105 said sections, for the purpose specified.

9. In a carriage, the combination with an 110 axle, of a support for said axle made up of sections; a coupling for said sections, having a cylindrical portion and parallel side portions adapted to receive the ends of said sections; rivets for pivotally securing said sections in said coupling; and a coiled spring arranged in the cylindrical portion of said coupling to engage 115 said sections, for the purpose specified.

10. In a carriage, the combination with a 120 body, of an axle; a support for said axle, made up of sections, one of the sections being connected to said body and the other to said axle; a coupling for said sections adapted to receive the ends thereof; rivets for pivotally 125 securing said sections in said coupling; and a coiled spring arranged in said coupling to engage said sections, for the purpose specified.

11. In a carriage, the combination with a 130

body, of an axle; a support for said axle, made up of sections one of the sections being connected to said body and the other to said axle; a coupling for said sections adapted to receive the ends thereof; rivets for pivotally securing said sections in said coupling; and a spring arranged in said coupling to engage said sections, for the purpose specified.

12. In a folding carriage, the combination 10 with the fixed side pieces; adjustable side-pieces pivoted thereon; wheels carried by said side pieces; side rails to which said adjustable side pieces are slidably connected pivoted to said fixed side pieces; a seat carried by said side rails; upwardly extending projections at the rear ends of said side rails adapted to close between said fixed side pieces when said seat is folded, said projections having outwardly projecting lugs thereon; and depressions in said side pieces adapted to be engaged by said lugs whereby the parts are held in their folded position.

13. In a folding carriage, the combination 25 with the fixed side pieces; adjustable side-pieces pivoted thereon; wheels carried by said side pieces; side rails to which said adjustable side pieces are slidably connected pivoted to said fixed side pieces; a seat carried by said side rails; and projections on 30 said side rails adapted to engage said fixed

side pieces whereby the parts are automatically locked in their folded position.

14. In a carriage, the combination of a body; an axle; a support for said axle comprising a pair of members, one of said members being connected to the body and the other to the axle; a coupling to which said members are pivotally connected, and a spring connection for said members, adapted to be placed under stress on the movement 40 of the said members on their pivots, for the purpose specified.

15. In a carriage, the combination with a body, of an axle; a support therefor comprising a pair of members one of said members being connected to the body and the other to the axle; and a coupling by which said members are connected including a spring adapted to hold said members in their normal position and to be placed under stress on the movement of said members relative to each other, for the purpose specified.

In witness whereof, I have hereunto set my hand and seal in the presence of two witnesses.

OTTO KURZ. [L. S.]
